UNITED STATES PATENT OFFICE.

CHARLES DE LUKACSEVICS, OF NEWARK, NEW JERSEY, ASSIGNOR TO DANE MANUFACTURING COMPANY, OF NEWARK, NEW JERSEY, A CORPORATION OF NEW JERSEY.

CARBURETER.

1,190,125.

Specification of Letters Patent.

Patented July 4, 1916.

Application filed December 4, 1915. Serial No. 65,087.

To all whom it may concern:

Be it known that I, CHARLES DE LUKACSEVICS, a citizen of the United States, residing at Newark, in the county of Essex and State 5 of New Jersey, have invented new and useful Improvements in Carbureters, of which the following is a specification.

This invention relates to carbureters for internal combustion engines and more particularly to a carbureter of that type where-in gasolene vapor is delivered to the air which makes up the explosive mixture through the agency of an absorbent element preferably composed of felt and partially 10 submerged in the liquid gasolene in the fuel supply chamber. In connection with carbureters of this type, it has been proposed to regulate the degree to which the absorbent gasolene distributing element is exposed to 15 the in-coming air in accordance with the speed at which the engine is to be operated. Thus, when the engine is to run at a minimum speed, a minimum area of the absorbent distributing element will be exposed, 20 and as the speed of the engine is increased, the exposed area of the distributing element will be correspondingly increased. According to the present invention, these operations are carried out by a construction 25 which, in connection with the regulation of the degree to which the absorbent distributing element is exposed to the air passing to the mixing chamber or motor suction tube, also effects a regulation of the degree to 30 which the said element is submerged in the liquid gasolene in the supply chamber. Thus, for a minimum exposure of the absorbent gasolene distributing element to the air passing through the carbureter there will 35 be a minimum submergence of said element in the liquid gasolene; and as the degree of exposure of the absorbent distributing element to the air is increased, its degree of submergence in the liquid gasolene will be 40 correspondingly increased. These operative effects attain the principal object of the invention which is to provide for the greatest accuracy and facility in regulating the quantum and richness of the mixture in accordance with any speed throughout the full 45 range of which the engine is capable.

A further object of the invention is to provide a carbureter of the type and for the purposes stated which shall be of ex-

ceedingly compact, simple and durable construction; in which the various operative parts are readily accessible for the purposes of cleaning, renewal or repairs; and in which no adjustments are entailed by the dismantling or the assemblage of the various 55 parts.

Embodiments of the invention are illustrated in the accompanying drawings wherein:—

Figure 1 is a central vertical sectional view 65 of a carbureter in which the features of the invention are incorporated. Fig. 2 is a horizontal section on the line 2—2 of Fig. 1, the rotatable element which carries the felt distributing blocks being shown partly in elevation. Fig. 3 is a plan view of a slightly modified construction, the mixing chamber appearing in section. Figs. 4, 5, 6 and 7 are fragmentary diagrammatic plan views 70 of the construction illustrated in Fig. 3 showing different positions of the distributing element for speeds varying from minimum to maximum. Figs. 8, 9, 10 and 11 are diagrammatic sectional views of the distributing element in positions which correspond to the positions in which said element is shown in Figs. 4 to 7, respectively. The dotted line A—B indicates a normal gaso- 75 len level common to the several positions in which the regulating element is shown in 80 these figures.

Similar characters of reference designate corresponding parts throughout the several views.

The carbureter shown in Figs. 1 and 2 includes a mixing chamber 1 for connection in the usual manner to the motor suction tube, an air inlet pipe 2 communicating with the lower end of the mixing chamber 1, a float feed chamber 3 at one side of the mixing chamber and a distributing element 4 constructed to deliver gasolene from the float feed chamber in the form of gasolene vapor to the air passing upwardly through the mixing chamber.

The mixing chamber 1 is preferably provided at a point above the distributing element 4 with a throttle valve 5 of the wing or butterfly type. The air inlet pipe 2 is preferably provided with a suitable regulating valve 6 by which the absolute amount of air delivered by said pipe may be accurately regulated. The communication of the pipe

2 and the mixing chamber 1 is preferably controlled by a spring held valve 7 whose spring 8 is regulated by a nut 9.

5 The distributing element 4 is formed as a cylinder in the embodiment disclosed, and is fitted within a cylindrical sleeve or casing 10 communicating with the mixing chamber 1 by a slot 11 extending longitudinally of the casing 10. The cylinder which constitutes the distributing element 4 is provided with end journals 12 and 13, the former having its bearing in a wall plate 14 and the latter having its bearing in a web 15 which closes one end of the casing 10. The said 10 casing is provided beyond the web 15 with an annular extension 16 which carries a closure cap 17 and provides a chamber 18 external to the casing 10. The chamber 18 communicates with the float feed chamber 3 by a duct 19, and with the interior of the distributing cylinder 4 by a duct 20 formed axially through the trunnion 13.

In order that the distributing cylinder 4 may have an accurate and secure fit in the 25 casing 10, it is pressed toward the web 15 by a spring 21 which bears between the closed end of said cylinder and the wall plate 14; and the trunnion 13 of said distributing cylinder has a conical end which 30 fits in a conformable opening in a packing gland 22 carried by the web 15.

The distributing cylinder 4 is a fuel reservoir or holder, the gasoline being supplied thereto by the duct 20, and said cylinder is 35 instrumental in delivering gasoline vapor to the air which passes through the mixing chamber through the agency of absorbent blocks 23, preferably of felt, which are set radially into the wall of the cylinder 4 and 40 have their exposed faces flush and conformable to the outer circumferential face of said cylinder. The felt blocks 23 extend between the inner and outer circumferential faces of the regulating cylinder 4 and project somewhat 45 into the interior of said cylinder. The blocks 23 are always partly submerged in the liquid gasoline and the degree of their submergence depends on the position of the cylinder 4. Said blocks are also disposed 50 whereby their exposure to the air passing through the mixing chamber will be of gradually increasing or decreasing character. This effect may be attained in various ways, but in Fig. 1 it is attained by disposing 55 the blocks 23 along a line which extends obliquely to the axis of the cylinder and by making the slot 11 of sufficient width to effect simultaneous exposures of all the felt blocks employed.

60 The operation of the distributing cylinder 4 is preferably correlated to the operation of the throttle valve 5, and for this purpose, the stem of said throttle valve carries, externally of the mixing chamber 1, an arm 24 65 which is connected by a link 25 to an arm 26

provided on the trunnion 12. The arm 24 engages a stop screw threaded in a lug on the carburetor casing (shown in dotted lines in Fig. 2) to limit the opening movement of the throttle valve.

When the engine is running at its minimum or "throttling" speed, the felt blocks 23 will be completely concealed by that portion 10^a of the casing 10 at the upper side thereof which intervenes between the mixing chamber 1 and the float feed chamber 3, except for a small fractional part of the surface of the block 23 at one end of the cylinder 4, specifically, in the embodiment shown, at that end of said cylinder which adjoins the trunnion 13. As the speed of the engine is increased, the cylinder 4 is turned counter-clockwise to proportionately increase the degree of exposure of the felt blocks 23 through the slots 11 and the degree of submergence of said blocks in the liquid gasoline. This will be apparent from Fig. 2 wherein the normal gasoline level is indicated by the line A—B. As the speed of the engine is diminished, the cylinder 4 is turned in clockwise direction, thereby proportionately diminishing the degree of exposure of the felt blocks 23 and the degree of submergence of said blocks in the liquid gasoline. In this way, the quantum and richness of the mixture is accurately regulated in accordance with any speed of the engine throughout its full range.

The mixing chamber 1 preferably has a constriction 27 in its outer wall at the elevation of the slot 11 in order that the air may be deflected in an obliquely lateral direction across the exposed felt distributing elements.

The modified construction shown in Fig. 3 is the same as that described as regards its principles of organization and operation, the difference consisting solely in the arrangement of the felt blocks. In this case, the casing 10 has an opening 11^a in substitution for the slot 11, this opening being of generally oval outline and the felt blocks, here designated 23^a, are arranged in different rows disposed longitudinally of the cylinder 4. If desired, and as shown, the blocks 23^a may be differentiated as to the sizes, the blocks which are exposed earlier being of greater diameter and those which are exposed last being of less diameter.

Figs. 4 and 8 show the position of the distributing cylinder 4 when the engine is running at minimum or "throttling" speed, in which position a portion of only one of the blocks 23^a is exposed. Figs. 5 and 9 show a position of the distributing cylinder 4 for a low speed, greater, however, than the throttling speed, wherein one of the blocks 23^a is completely exposed and two adjoining blocks are partly exposed. Figs. 6 and 10 show a higher position of the distributing

cylinder 4 for a higher speed wherein three of the blocks 23^a are completely exposed and the remaining two blocks are partly exposed. Fig. 11 shows the position of the distributing cylinder 4 for the maximum speed and wherein all of the blocks 23^a are completely exposed. The line A—B common to Figs. 8 to 11 indicates the normal fuel level, and by reference to this line, it will be noted that as the exposed area of the felt increases, the submergence of the felt blocks in the liquid gasoline correspondingly increases. Fig. 2 shows the felt blocks 23 as shouldered and as held in shouldered openings provided therefor by supporting posts 28. Figs. 8 to 11 show a slight modification in the assemblage of these blocks, according to which the blocks 23^a are fitted in threaded openings between the circumferential faces of the cylinder 4 and the posts 28 are dispensed with.

The invention is believed to be of considerable novelty within its particular field and it will, therefore, be understood that no specific description herein contained is intended to put any limitation upon the scope of the appended claims which does not inhere in the language thereof.

Having fully described my invention, I claim—

1. In a carbureter for internal combustion engines, in combination, a mixing chamber, a fuel supply chamber, absorbent fuel distributing means submerged in the liquid fuel and arranged intermediate said chambers, and means for progressively and simultaneously increasing the exposure of said absorbent means in said mixing chamber and the submergence of said means in the liquid fuel, or, in like manner decreasing such exposure and submergence.

2. In a carbureter for internal combustion engines, in combination, a mixing chamber, a fuel supply chamber, and a regulating element provided with absorbent fuel distributing means exposed in said mixing chamber and submerged in the liquid fuel of said supply chamber, said element being operable to progressively and simultaneously increase the exposure of said absorbent means in said mixing chamber and the submergence of said means in the liquid fuel, or, in like manner, to decrease such exposure and submergence.

3. In a carbureter for internal combustion engines, in combination, a mixing chamber, a fuel supply chamber, and absorbent fuel distributing means submerged in the liquid fuel and arranged intermediate said chambers, said absorbent means being operable whereby its exposure in said mixing

65
ber and its submergence in the liquid fuel are progressively and simultaneously increased or decreased as the case may be, or, in like manner, whereby such exposure and submergence are decreased.

4. In a carbureter for internal combustion engines, in combination, a mixing chamber, a fuel supply chamber, a casing having an opening communicating with the mixing chamber, a regulating cylinder rotatably fitted in said casing and having a connection with said fuel supply chamber, and absorbent means carried by said cylinder for exposure to said mixing chamber through said opening, said absorbent means being submerged in the liquid of said supply chamber and being arranged whereby, upon a rotation of said cylinder, its exposure through said opening and its submergence in the liquid fuel is progressively and simultaneously increased or decreased as the case may be.

5. In a carbureter for internal combustion engines, in combination, a mixing chamber, a fuel supply chamber, a casing having an opening communicating with the mixing chamber, a hollow regulating cylinder rotatably fitted in said casing and having a connection with said fuel supply chamber, and a plurality of absorbent blocks carried by said cylinder for exposure to said mixing chamber through said opening, said blocks being submerged in the liquid of said supply chamber and being arranged whereby, upon a rotation of said cylinder, their exposure through said opening and their submergence in the liquid fuel is progressively and simultaneously increased or decreased as the case may be.

6. In a carbureter for internal combustion engines, in combination, a mixing chamber, a fuel supply chamber, absorbent fuel distributing means submerged in the liquid fuel and arranged intermediate said chambers, said absorbent means being operable whereby its exposure in said mixing chamber and its submergence in the liquid fuel are progressively and simultaneously increased or decreased as the case may be, a throttle valve in said mixing chamber, and means for correlating the operations of said absorbent means and said throttle valve.

In testimony whereof I have hereunto set my hand in presence of two subscribing witnesses.

CHARLES DE LUKACSEVICS.
